UNITED STATES PATENT OFFICE.

UBERT URQUHART, OF NEW YORK, N. Y., ASSIGNOR TO THE AUTO PNEUMATIC ACTION COMPANY, OF NEW YORK, N. Y., A CORPORATION OF NEW YORK.

TENSION-CONTROLLING MECHANISM FOR MUSICAL INSTRUMENTS.

Application filed January 10, 1924. Serial No. 685,341.

The object of this invention is to provide a new and improved tension controlling mechanism for pneumatically operated musical instruments whereby the dynamic effects can be controlled.

The invention has been particularly designed for use in combination with an accenting instrument which is operated from two sources of tension; one relatively high and the other relatively low; the high tension being applied automatically to selected notes to obtain solo effects. While the improved tension controlling mechanism can be applied substantially to any accenting instrument, I have particularly designed and shown the same herein as applied to the accenting mechanism shown and described in an application for patent filed by Herbert J. La Joie and Ubert Urquhart, 20 Sept. 14, 1922, Serial No. 588,254.

The improved tension controlling mechanism has been designed to work primarily in a suction or exhaust operating mechanism; and the particular feature thereof consists 25 in providing an adjusting valve for controlling a passage from the action to the suction pump; a spring pressed pneumatic for operating said valve, and a valve operated from the tracker-bar for controlling 30 said pneumatic, the passage for operating the pneumatic against the spring being restricted in size, while the passage from the atmosphere to the pneumatic is large, whereby the time element of the position 35 of the perforation in the music sheet for operating said pneumatic relatively to the position of the playing perforation or perforations controls the dynamic effect. This dynamic effect is preferably built up on a 40 governed tension which is the slightest or softest the instrument is to play. The pneumatic above mentioned preferably is operated from an accurately governed source of tension so that the time element can be 45 nicely figured.

Preferably two such mechanisms are employed with each tension. This adjusting valve mechanism also preferably is duplicated so that said mechanism will automatically control the tension which operates either or both the accented or accompaniment notes.

One form of apparatus by which my invention can be conveniently practiced is il-

lustrated in the accompanying six sheets of drawings, referring to which—

Fig. 1 is a diagrammatic elevation illustrating a player piano action with my invention applied thereto.

Fig. 2 is a front elevation on an enlarged scale partly in section of the accent control valve chest.

Fig. 3 is a bottom plan view partly in section in the line 3—3 of Fig. 2.

Fig. 4 is a cross sectional elevation there- 65 of on the line 4—4 of Fig. 1.

Fig. 5 is a diagrammatic view illustrating the perforated music sheet, tracker-bar, and the connections by which the accenting is obtained.

Fig. 6 is a front elevation partly in section illustrating the tension controlling mechanism.

Fig. 7 is an end elevation thereof.

Fig. 8 is a plan thereof.

Fig. 9 is a sectional plan on the line 9—9 of Fig. 6.

Fig. 10 is a cross sectional elevation on the line 10—10 of Fig. 6.

Fig. 11 is an enlarged view of the ten- 80 sion controlling valves and operating pneumatics therefor.

Fig. 12 is a cross sectional elevation on the line 12—12 of Fig. 11.

Fig. 13 is a detailed view of one of the 85 springs which controls the adjusting pneumatic.

Fig. 14 is a partial cross sectional plan on the line 14—14 of Fig. 11.

Fig. 15 is a plan illustrating the relative 90 arrangement of the two springs used in connection with two of the adjusting pneumatics, and

Fig. 16 is a diagrammatic plan of the tracker-bar and music sheet, illustrating 95 diagrammatically the connections to the tension controlling mechanisms.

Referring to the drawings and in detail, I will first describe in general terms the accenting mechanism to which my improvement is to be applied and reference to follow this description should be had to the first three sheets of drawings.

These drawings illustrate a tracker-bar and music sheet manipulating mechanism arranged in any of the improved ways, above an action valve chest, which carries the usual striker pneumatics having connections for

operating the actions of the piano as illustrated particularly in Fig. 4. The action valve chest contains partitions 100 as illustrated in Figs. 1 and 5 so that the tracker-controlled valves V will be divided into sections. As shown there may be nine intermediate sections of three valves each and the remainder of the valves may be divided between the bass and treble sections. On top of the action chest is arranged an accent control valve chest W having passages G and H, the passage G being a low tension passage for the accompaniment and the passage H being a high tension passage for the accent. The accent control valve chest W is provided with nine valves C, which control passages extending to the nine sections in the valve chest, and with two jointly acting valves C¹ controlling passages extending to the bass section of the action valve chest and with two jointly acting valves C² controlling passages extending to the treble section of the action valve chest. These valves are controlled by eleven expression openings arranged in the tracker-bar, five at the left thereof and six at the right thereof, as illustrated particularly in Fig. 5. The normal playing is obtained from the lower tension in the accompaniment passage G. If any note is to be accented, the proper one of the eleven accent openings in the tracker is uncovered, by an accent-controlling perforation in the music sheet, which will set the proper valve C, C¹ or C², as the case may be, so that the air from the particular section of the action valve chest, instead of being exhausted through the passage G, will be exhausted through the passage H, which is connected to the high tension so that the particular note thus will be accented. Thus the piece of music can be played to produce solo effects, that is particular notes may be accented or played louder than the remaining or accompanying notes.

The details of this accenting mechanism are set forth more in detail in said application for patent, Serial No. 588,254, previously referred to.

I will now describe the tension controlling mechanism, by which the tension of either or both the accent or accompaniment may be automatically controlled from the tracker-bar. The suction pump is connected by a pipe 20 to the back block 21 of the tension controlling device and to a horizontal passage 22 therein. The tension controlling device is constructed so as to contain two chambers 23 and 24; the chamber 23 being connected by a pipe 25 to the accent passage in the accent control valve chest and the chamber 24 being connected by a pipe 26 to the accompaniment passage in the accent control valve chest. The chambers 23 and 24 are covered by a suitable front board 230, which is shown as removed in Figures 6 and 11.

The valve arrangement in each chamber 23 and 24 is substantially the same and the arrangement in the accompaniment chamber 24 will be described in detail.

The passage 22 is connected by a passage 27 to the chamber 24, this passage being controlled by a pivoted spring pressed governor valve 28, which is regulated by a pneumatic 29 adjustably connected thereto by link 30. The pneumatic 29 is normally kept open by an adjustable spring 31 and the pneumatic is connected to the chamber 24 by a passage 32. These parts are arranged so that normally the lightest or softest tension employed will be maintained in the chamber 24. A long narrow vertical passage 33 is arranged between the chamber 24 and the passage 22, which passage 33 is controlled by a sliding valve 34, arranged to move vertically in ways or guides 35, 350. This valve is adjustably connected by a wire or rod 36 to an adjusting pneumatic 37 arranged at the left hand top of the structure, this pneumatic being normally forced open by a spring 38 arranged on the side thereon, whereby the sliding valve 34 will be held upwardly normally to cover the passage 33. A third compartment 39 is arranged at the right hand part of the structure and the same is connected by a passage 40 to the passage 22. This passage is controlled by a pivoted spring pressed governing valve 41, which is adjustably connected to a pneumatic 42, arranged on the right hand side of the structure, which pneumatic is connected to the compartment 39 by a passage 43, as indicated in dotted lines in Fig. 6. The pneumatic 42 is normally kept extended by an adjustably arranged spring 44. By this arrangement an accurately governed tension will be maintained in the compartment 39. This third compartment is connected by a passage 45 to a passage 46 in a block 47. A double valve 48, see Fig. 12, is arranged to control a passage 49 extending to the adjusting pneumatic 37, so as either to leave the pneumatic connected to the atmosphere through a passage 50 in the top of the block 47 or to connect the pneumatic to the passage 46. It will be seen that the tension in the passage 46 is an accurately governed tension, so that the operation of the adjusting pneumatic 37 can be readily regulated. The connection between the passage 46 and the passage 49 is made minute or restricted in size, a bleed or perforated metal cap 51 being preferably employed, while the passage from the governing pneumatic to the atmosphere is relatively very large. With this arrangement, when the double valve 48 is lifted to connect the passage 46 with the passage 49 to collapse the adjusting pneumatic 37, this action will take place very slowly as the air can only flow very slowly through the bleed 51. On the other hand when the double

valve 48 is in its normal position, as illustrated in Fig. 12, the atmospheric air can flow at high speed into the adjusting pneumatic so that the opening movement thereof will be almost instantaneous. The valve 48 is operated by a diaphragm 52 having a bleed control compartment 53 below the same, which is connected by a tube 54 to a tension control opening 55 in the tracker. This controlling mechanism preferably is duplicated. A long passage 330 is arranged between the passage 22 and the chamber 24, this passage 330 being considerably wider than the passage 33. This part of the tension control mechanism is controlled by a sliding valve 340 arranged in guides 350 and 351, which sliding valve is connected by wire 360 to governing pneumatic 370 normally held open by spring 380. This adjusting pneumatic 370 is operated by a double valve arranged in the block 47 and is similar in construction to the double valve already described. This double valve is controlled through a tracker opening 57 next to the opening 55, as illustrated in Fig. 16. The chamber 23 which is arranged to control the dynamics of the accent is provided with similar governing valves, etc., which it is not believed necessary to describe again.

The operation is as follows, the description being given of the operation in connection with the chamber 24 controlling the accompaniment. The tension in this chamber is normally maintained by the governing valve 28 at the lowest or softest which is to be employed for playing. When a note or series of accompaniment notes is to be played louder, a tension control opening is cut in the music sheet in proper time relation. For example, perforation 60 is cut a slight distance ahead of the playing perforation 61, whereby the sliding valve 34 will be slightly lowered before the note 61 is called, thereby playing the same with a slightly increased force, the degree of increase being determined by the advance of the perforation 60 relatively to perforation 61. If the next note is to be played louder the tension control opening 62 is given an increased lead relatively to the playing perforation 63. By figuring the advance of the tension control perforation relatively to the playing perforation or perforations within the limits of the action obtained by the valve 34, various pressures can be established to control the dynamics because the slow opening movement of the valve 34 is controlled by these tension control perforations.

In case it is desired to go above the degree of tension which can be obtained by the valve 34, recourse is had to the operation of the valve 340, which controls the larger passage 330, that is, perforation 70 will give a larger degree of tension for playing perforation 71; 72 still louder for 73; 74 still louder for 75; and 76 still louder for 77. As many tension control valves 34-340 can be employed as desired but I have found two sufficient. The valves 34 and 340 may be made to work together if desired by arranging the tension control openings side by side but I have found it usually better to operate only one valve 34 or 340 at a time.

The dynamics of the accent are similarly controlled from the chamber 23, which is connected by the pipe 25 to the accent passage in the accent control valve chest. The spaces under the diaphragm of the valve 48-48 of this part of the tension control apparatus are connected by pipes 540 and 560 to tension control openings 550 and 570 at the right hand end of the tracker bar, as illustrated in Figure 16 and the same general operation is obtained with the heavier pressure given the accented notes. For instance, the time element of the tension control perforation 600 will cause the note called by the perforation 610 to be played with a certain tension, while the time element of the tension control 620 will cause the note called by the perforation 630 to be played with a heavier tension. Of course while the tension control of the accented notes is to be regulated, accenting perforations such as X and X¹ must be arranged in conjunction with the playing perforations. The springs for controlling two governing pneumatics 29 are preferably made slightly different in size as illustrated in Fig. 15, the spring on the pneumatic controlling the accenting part of the action being somewhat shorter and stiffer than the spring on the other pneumatic, so that the tension on the accented notes normally will be kept somewhat higher than the tension on the accompaniment notes so that the accented notes normally will be played somewhat louder. The same results could be obtained by adjusting the tension of the springs but I have found it is preferable to employ springs of different lengths for this purpose. By adjusting the connection between the valve 41 and the pneumatic 42 or by adjusting the tension of the spring 44, it will be seen that the tension at which the adjusting pneumatics 37 and 370 operate can be regulated, whereby the relative dynamic effects obtained from the tension control perforations in the music sheet can be adjusted. By the arrangements described it will thus be seen that a simple mechanism is provided for controlling dynamic effects, which mechanism can be advantageously applied to an accenting mechanism.

The details and arrangements herein shown and described may be greatly varied by a skilled mechanic without departing from the scope of the invention as expressed in the claims.

Having thus fully described my invention

what I claim and desire to secure by Letters Patent is:—

1. A tension controlling mechanism for musical instruments comprising an adjusting valve controlling a passage from the action to the pump, a spring pressed pneumatic for operating said adjusting valve, and a valve operated from the tracker for controlling said pneumatic, the passage for 10 operating the pneumatic against the spring being restricted in size, whereby the time element of the position of the perforation in the music sheet for operating said pneumatic relatively to the position of the playing perforation or perforations controls the intensity of the dynamic effect.

2. A tension controlling mechanism for musical instruments, comprising an adjusting valve controlling a passage from the action to the pump, a spring pressed pneumatic for operating said adjusting valve, and a valve operated from the tracker for controlling said pneumatic, the passage for 20 operating the pneumatic against the spring being restricted in size, while the passage from the atmosphere to the pneumatic is large, whereby the time element of the position of the perforation in the music sheet for operating said pneumatic relatively to 25 the position of the playing perforation or perforations controls the intensity of the dynamic effect.

3. A tension controlling mechanism for musical instruments, comprising two adjusting valves controlling passages of relatively different sizes from the action to the pump, spring pressed pneumatics for operating said adjusting valves, and valves operated from the tracker for controlling said 30 pneumatics, the passages for operating the pneumatics against their springs being restricted in size, whereby the time element of the position of the accenting perforations in the music sheet relatively to the position of 35 the playing perforation or perforations controls the intensity of the dynamic effects.

4. A tension controlling mechanism for musical instruments, comprising a chamber connected to the action, a governing device 50 for maintaining a low constantly regulated tension therein, an adjusting valve controlling a passage from said chamber to the pump, a spring pressed pneumatic for operating said adjusting valve, and a valve operated from the tracker for controlling said pneumatic, the passage for operating the pneumatic against the spring being restricted in size, whereby the time element of the position of the perforation in the music 55 sheet for operating said pneumatic relatively to the position of the playing perforation or perforations controls the intensity of the dynamic effect.

5. A tension controlling mechanism for 60 musical instruments comprising an adjust-

ing valve controlling a passage from the action to the pump, a spring pressed pneumatic for operating said adjusting valve, a governor for regulating the tension applied to operate said pneumatic, and a valve operated from the tracker for controlling said pneumatic, the passage for operating the pneumatic against the spring being restricted in size, whereby the time element of the position of the accenting perforation in the 75 music sheet for operating said pneumatic relatively to the position of the playing perforation or perforations controls the intensity of the dynamic effect.

6. A tension controlling mechanism for 80 musical instruments, comprising an adjusting valve controlling a passage from the action to the pump, a spring pressed pneumatic for operating said adjusting valve, a governor for regulating the tension applied 85 to operate said pneumatic, means whereby the governing effect thereof can be adjusted, and a valve operated from the tracker for controlling said pneumatic, the passage for operating the pneumatic against the spring 90 being restricted in size, whereby the time element of the position of the accenting perforation in the music sheet relatively to the position of the playing perforation or perforations controls the intensity of the dynamic effect.

7. In a pneumatically operated musical instrument, a source of air tension, an accompaniment air chamber and an accenting air chamber, means to provide a regulated 100 low air tension for said accompaniment chamber, means to provide a regulated high air tension for said accenting chamber, a plurality of striker pneumatics, means to selectively connect said striker pneumatics 105 to either air chamber, and record controlled means to increase the air tension in said accompaniment chamber for playing selected notes.

8. In a pneumatically operated musical 110 instrument, a source of air tension, an accompaniment air chamber and an accenting air chamber, means to provide a regulated low air tension for said accompaniment chamber, means to provide a regulated high 115 air tension for said accenting chamber, a plurality of striker pneumatics, means to selectively connect said striker pneumatics to either air chamber, and record controlled means to increase the air tension in said accenting chamber for playing selected notes.

9. In a pneumatically operated musical instrument, a source of air tension, an accompaniment air chamber and an accenting air chamber, means to provide a regulated low 125 air tension for said accompaniment chamber, means to provide a regulated high air tension for said accenting chamber, a plurality of striker pneumatics, means to selectively connect said striker pneumatics to either air 130

chamber, and record controlled means to increase the air tension in each of said air chambers for playing selected notes.

10. In a pneumatically operated musical instrument, the combination of a source of high air tension and a source of low air tension, mechanism whereby the high air tension may be applied automatically to operate and thus accent certain notes, and additional air tension controlling mechanism for automatically adjusting either the high air tension or the low air tension with respect to certain selected notes.
11. A tension controlling mechanism for musical instruments having player actions and an air pump, comprising an adjusting valve controlling a passage between said actions and the air pump, and automatic means for positioning said valve, said automatic means being responsive to the time element of the position of the perforations in the music sheet controlling said automatic means relative to the position of the associated playing perforation or perforations

for the player actions producing the notes to be accented, whereby the intensity of the dynamic effect is controlled by said time element.

12. In a pneumatically operated musical instrument, a source of air tension, an accompaniment air chamber and an accenting air chamber, means to provide a regulated low air tension for said accompaniment chamber, means to provide a regulated high air tension for said accenting chamber, a plurality of striker pneumatics, means to selectively connect said striker pneumatics to either air chamber, and additional means to increase the air tension in each of said air chambers for playing selected notes, the time element of the position of the accenting perforation in the music sheet relative to the playing perforation controlling the intensity of the dynamic effect.

In testimony whereof I have hereunto affixed my signature.

UBERT URQUHART.
